DESIGN FOR A SHOE

Gustav Peterson, New York, N. Y.

Application November 11, 1935, Serial No. 59,466

Term of patent 3½ years

To all whom it may concern:

Be it known that I, Gustav Peterson, a citizen of the United States of America, residing in Manhattan, county of New York, and State of New York, have invented a new, original, and ornamental Design for a Shoe, of which the following is a specification, reference being had to the accompanying drawing, forming part thereof, wherein,

Figure 1 is a plan view of a shoe showing my new design.

Figure 2 is a side elevational view of the shoe shown in Figure 1.

The dominant feature of my design resides in the combination of the straight tip with the skeleton wing tip, on the vamp portion of the shoe.

I claim:

The ornamental design for a shoe, substantially as shown, and described.

GUSTAV PETERSON.
